Patented Sept. 1, 1914.

THE NORRIS PETERS CO., PHOTO-LITHO., WASHINGTON, D. C.

UNITED STATES PATENT OFFICE.

SIXTEN A. ROSEN, OF WORCESTER, MASSACHUSETTS, ASSIGNOR OF ONE-HALF TO
HERMAN L. DOW, OF WORCESTER, MASSACHUSETTS.

MEAT AND FRUIT PRESS.

1,109,363.

Specification of Letters Patent.

Patented Sept. 1, 1914.

Application filed June 28, 1913. Serial No. 776,247.

To all whom it may concern:

Be it known that I, SIXTEN A. ROSEN, a citizen of the United States, residing at Worcester, in the county of Worcester and 5 State of Massachusetts, have invented a new and useful Meat and Fruit Press, of which the following is a specification.

This invention relates to the type of meat and fruit presses represented in my Patent 10 #1,058,792, granted on the 15th day of April, 1913.

The principal objects of this invention are to provide means for the construction of a press, of the type represented in my 15 above mentioned patent, by which the main frame and the connections for the plunger are made more rigid, durable and inexpensive.

More specifically, this invention involves 20 the provision of a set of supporting legs for the body of the device, formed of two pieces of metal and so arranged that by securing one of said pieces of metal to the body of the device, the other one will also 25 be firmly secured thereto.

Further objects and advantages of the invention will appear hereinafter.

Reference is to be had to the accompanying drawings in which—

30 Figure 1 is a side elevation of a preferred embodiment of the invention, showing the plunger in elevated position; Fig. 2 is a plan thereof; and Fig. 3 is a bottom plan of the under side of the container or holder for the fruit or meat to be pressed.

I have shown the invention herein as applied to a holder or container 10 of the same general form, and other characteristics as 40 in my above identified patent. It is provided with a vertical slot 11 for discharging the juice and with an integral ear at the upper and rear side thereof. This container is supported in a slanting position as was the case in the device shown in said patent.

45 For the purpose of so supporting it according to the present invention, a plate 12 of sheet metal is secured to the bottom of the holder 10 by rivets, or in any other desired manner. Before being applied this 50 plate is bent up so that its two ends will extend downwardly and outwardly at an angle from the lower corners of the container to form a pair of legs 13 of an L-shaped cross section. These legs are bent up at the bottom to form feet 14 in a plane.

The plate is shown as secured by two rivets and between these rivets the plate is bent downwardly at 15 so as to be spaced from the bottom of the holder for a distance. In securing this plate in place the flat end 60 16 of another metal piece is passed under the bent portion 15 and a flange 17 on the end of this flat plate extends downwardly under one edge of the plate 12. The opposite or upper end of the plate 16 is provided with two flanges 18 at right angles to it and engaging the top edge of the plate 12 so that this member is securely held in position when the plate 12 is affixed to the bottom. The second sheet metal member, 70 before being applied, is bent downwardly and outwardly to form a third leg 20 having two side flanges and these parts are bent out at the bottom to form a foot 21 in the plane of the feet 14. 75

The integral ear at the top of the holder is provided with a loose pivot pin 25 on which is pivoted a handle 26 which consists of a piece of sheet metal bent upon itself and having a curved form adjacent to 80 the pivot and then extending out straight. The ends of this sheet metal piece near the pivot are brought substantially into contact with each other while the two portions thereof at the upper end are separated from 85 each other to form a convenient grip at the end of the handle.

When securing the ends together near the pivot a rivet 27 is employed and this serves another purpose, namely, the securing to 90 the handle of a rod 28. This rod is formed of a single piece of sheet metal bent around the handle and having its two ends bent into contact with each other below the handle so that they form a strong rod. These 95 ends 29 are bent outwardly and secured to the flat plate 30 which constitutes the plunger.

The operation of the device as far as 100 pressing the fruit or meat is the same as in my above-mentioned patent and these improvements are made not to change the operation but to decrease the cost of manufacture, increase the durability, and render the device simpler to use and thus more easily 105 appreciated by parties who are called upon to use it.

It can be seen that the body is firmly supported and yet the legs are secured to the body in an exceedingly simple and inexpen- 110

sive manner and that also the plunger is supported in a very effective way and yet secured in position very simply.

Although I have illustrated and described only this specific embodiment of the invention, I am aware of the fact that modifications can be made therein by persons skilled in the art, without departing from the scope of the invention as expressed in the claims, therefore, I do not wish to be limited to all the details of construction herein shown and described but

What I do claim is:

1. As an article of manufacture a press comprising a container mounted at an inclination, a single piece of material secured to the bottom of said container and extending downwardly at an inclination from both of the lower corners thereof to form a pair of legs for assisting in supporting the container, and a third leg consisting of a single piece extending downwardly from the upper end of the bottom of the container and wholly secured in position on said container by said first named piece.
2. As an article of manufacture a press of the character described comprising a slanting container and a pair of legs extending down from the lower edge of said container, said legs having a plate integrally connecting their upper ends and located flat on the bottom of the container and secured thereto, said plate having an offset portion near the center of the container, and a third leg extending down from the upper edge of the

bottom of the container, terminating at the top of the flat plate, extending under said offset, and provided with a transverse flange at its extreme end so as to be held securely against the bottom of the container by said plate.

3. As an article of manufacture a press comprising an inclined container, a pair of legs extending downwardly from the opposite corners of the lower edge of the bottom of said container and being integrally connected with each other by a continuous portion secured against the bottom of the said container and having an offset portion in the center thereof spaced from the bottom of the container, and a third leg having a flat portion extending into the space between the offset portion of the first plate and the bottom of the container, securely held therein by said plate, and having a pair of edge flanges extending therefrom longitudinally thereof and a transverse flange at one end, by which flanges it is retained in position, said plate extending upwardly from the first named plate toward the upper edge of the bottom of the container and then being bent downwardly and outwardly therefrom.

In testimony whereof I have hereunto set my hand, in the presence of two subscribing witnesses,

SIXTEEN A. ROSEN.

Witnesses:

ALBERT E. FAY,
CATHARINE I. HARTNETT.
